United States Patent

Des. 235,284
Patented June 10, 1975

235,284

CHAIR

Don Ray Gill, Westville, Ind., assignor to Futorian Corporation, Amsterdam, N.Y.

Filed Sept. 11, 1973, Ser. No. 396,340

Term of patent 14 years

Int. Cl. D6—01

U.S. Cl. D6—37

The figure is a perspective view of a chair illustrating my new design.

The back of the chair is conventionally plain while the side not shown is substantially identical to the side shown.

I claim:

The ornamental design for a chair, as shown and described.
